UNITED STATES PATENT OFFICE.

ELI ADLER, OF BUFFALO, NEW YORK.

SAFETY BEAM-GRIP.

1,128,277.

Specification of Letters Patent. Patented Feb. 16, 1915.

Application filed July 18, 1914. Serial No. 851,809.

To all whom it may concern:

Be it known that I, ELI ADLER, a citizen of the United States, residing at Buffalo, in the county of Erie and State of New York, have invented new and useful Improvements in Safety Beam-Grips, of which the following is a specification.

This invention relates to a safety grip which is more particularly designed for lifting beams such as steel I-beams used in the construction of buildings, bridges, &c. The devices heretofore used for gripping or fastening such beams to the tackle of a hoisting apparatus have not been entirely satisfactory on account of the insecure hold obtained by such devices on the beams which frequently resulted in releasing the same and endangering life and property.

It is the object of this invention to provide a safety grip which can be produced at low cost, which can be easily and quickly applied to and removed from the beam and whereby beams and the like may be securely grasped and connected with the hoisting tackle without liability of slippage of the beam and possible dropping of the same while being hoisted or transported from one place or another.

In the accompanying drawings: Figure 1 is a side elevation of a safety beam grip constructed in accordance with my invention and showing the same detached from the beam. Fig. 2 is a similar view showing the same attached to a beam. Fig. 3 is an end elevation of the grip applied to a beam. Fig. 4 is a horizontal section taken in line 4—4, Fig. 2.

Similar characters of reference indicate corresponding parts throughout the several views.

My improved safety beam grip preferably comprises two upright levers 1, 1 which cross each other and are connected by a horizontal transverse pivot or bolt 2 so that these levers are capable of swinging in a vertical plane relatively to each other. The upper arms of these two levers may be connected with the tackle of a hoisting apparatus in any suitable manner so that an upward pull upon these upper arms causes the same to move toward each other and the lower arms thereof to also move toward each other for gripping the beam which is to be lifted or transported. As shown in the drawings, the means for thus drawing the upper arms of the levers together comprise two chains or

flexible members 3—3 which are connected at their outer ends with the upper arms of the levers while their inner ends are connected with a lifting or attaching ring 4, 60 the latter being intended to receive the hook or other member of the hoisting apparatus. At the lower end of each lever arm the same is provided with an upper downwardly facing gripping jaw 5 which is preferably 65 beveled or inclined so that the faces of the upper gripping jaws of both levers diverge downwardly in the operative position of these levers, as shown in Fig. 2. These upper gripping jaws of the levers are adapted 70 to engage with the upper side of the upper flanges 6 of an I-beam at the upper outer corners of these flanges when gripping such a beam, as shown in Fig. 2.

7, 7 represent two claws each of which is 75 pivotally connected at its upper end by means of a horizontal transverse pivot bolt 8, or other suitable means, with the lower arm of one of the levers above the upper jaw thereof. Each of these claws is curved or 80 of C-shaped form and extends from its pivotal connection with the respective lever arm outwardly, downwardly and inwardly relatively to this arm. On its lower part the claw is provided with a lower upwardly 85 facing gripping jaw 10 which is adapted to engage with the underside of one of the upper flanges of the I-beam adjacent to the place where this flange is engaged on its upper side by the lower jaw of the companion lever, as shown in Fig. 2. Each of 90 these claws is preferably provided in its upper part with a vertical slot 9 which receives the lower arm of the companion lever, thereby providing a balanced support 95 for the claw on the lever and causing these parts to be guided one upon the other so that they do not become displaced or distorted while subjected to the strains of the load which is being carried. 100

When this grip is applied to a beam and the weight of the latter is suspended by the grip the inclined upper jaws of the levers engage with the opposite upper corners of the beam with a wedging or pinching action 105 and the lower jaws of the claws engage with the undersides of the upper flanges of the I-beam, as shown in Fig. 2. While the beam is thus suspended by the grip its weight causes the lower arms of the levers to constantly tend to approach each other whereby the inclined jaws of the levers are caused 110

to press the upper flanges of the I-beam with a wedging or pinching action against the lower jaws of the claws. The frictional hold of the several jaws of the grip upon the I-beam is thus increased in proportion to the increased weight of the beam which is being lifted and the latter is securely connected with the lifting device.

Owing to the wedge or pinch action of the levers which engage the upper side of the beam and cause the underside of the beam flanges to be pressed against the lower jaws of the claws, slippage of the beam on the grip while thus engaged is positively prevented, thereby insuring absolute safety to the workmen and other nearby persons and also avoiding damage to property as is otherwise inevitable when a beam drops by becoming detached from the hoisting tackle.

I claim as my invention:

1. A safety beam grip comprising two crossed and pivotally connected levers each of which is provided at its lower end with an upper gripping jaw adapted to engage with the upper side of a beam, and claws pivoted on the lower ends of said levers and each provided with a lower gripping jaw which is adapted to engage with the underside of a beam.

2. A safety beam grip comprising two crossed and pivotally connected levers each of which is provided at its lower end with an upper gripping jaw adapted to engage with the upper side of a beam, and claws which are pivoted on said levers and each of which curves from its pivot outwardly, downwardly and inwardly and is provided at its lower end with a lower gripping jaw adapted to engage with the underside of the beam.

3. A safety beam grip comprising two crossed and pivotally connected levers each of which is provided at its lower end with an upper inclined gripping jaw adapted to engage with the upper side of a beam, and claws which are pivoted on said levers and each of which is provided in its upper part with a vertical slot for the reception of the companion lever and on its lower part with a lower jaw for engagement with the underside of the beam.

Witness my hand this 15th day of July, 1914.

ELI ADLER.
